UNITED STATES PATENT OFFICE.

WALLACE CASWELL, OF CHEROKEE, IOWA.

BALING-MACHINE.

1,274,682.

Specification of Letters Patent.

Patented Aug. 6, 1918.

Application filed October 29, 1915. Serial No. 58,676.

To all whom it may concern:

Be it known that I, WALLACE CASWELL, a citizen of the United States, residing at Cherokee, county of Cherokee, State of Iowa, have invented certain new and useful Improvements in Baling-Machines; and I do hereby declare the following to be a full, clear, and exact description of the invention, such as will enable others skilled in the art 10 to which it appertains to make and use the same.

The invention relates to presses for baling hay, straw and the like, in which the compression of the material is effected by means 15 of a reciprocating plunger and the tying or wiring of the bale is accomplished automatically by apparatus which feeds the wire around the bale, loops the ends thereof together and twists the looped ends, and finally 20 severs the wire adjacent to the looped tie, after which the finished bale is discharged from the compression chamber.

In the accompanying drawings Figure 1 is the side elevation of the baling press; Fig. 25 2 is a plan view of the mechanism which engages and disengages the wire tying and feeding apparatus with the baling press; Fig. 3 is a rear end view of the two wire looping and twisting members; Fig. 4 is a 30 view of one wire looping and twisting member showing the needle as having passed across the face of the member and the wire looped around the pin; Fig. 5 is an advanced stage view showing the wires twisted; Fig. 35 6 is a further advanced stage showing the wire severed from the looping member, and the needles passed back through the baling chamber; Fig. 7 is a detail view of the driving mechanism of the wire tying apparatus; Fig. 40 8 is a detail view of the wire twisting mechanism; Fig. 9 is a detail view of the driving mechanism of both the wire feeding and wire tying mechanism; Fig. 10 is a plan view of one needle, the dotted line showing 45 the position of the wire when the needle has passed through the baling chamber, the full line showing the position of the wire when the needle is standing at rest outside the chamber; Figs. 11, 12 and 13 are sectional 50 views of the wire clamping and shearing mechanism; Figs. 14 and 15 are sectional views of the wire hook or guide; Fig. 16 is a fragmental plan view of the compression chamber showing the location of the spools, 55 the course of the wire, and showing, in full lines, the location of the needle when it is

in its rearward end of travel, and, in dotted lines, its position when it is in its forward end of travel; Fig. 17 is an enlarged view of the mechanism which engages and disengages the carriages and locks one of the carriages at rest; Fig. 18 is a fragmental view showing the gear 3' and the position in which it is located with respect to the gear 3; Fig. 19 is a fragmental side elevation of 60 the disk 57 showing it in one of its positions in full lines, and in its other position in dotted lines; and Fig. 20 is a fragmental view illustrating the driving mechanism for the wire-looping and wire-twisting mechanisms, the view being taken from the opposite side to that illustrated in Fig. 1.

By referring to the drawings you will note that the machine comprises a baling chamber, which may be, either of the continuous or the box type, and a reciprocating plunger operating longitudinally in the chamber to compress successive charges of the material which is fed into the chamber loose, and there compressed into a bale; 75 two carriages slidably mounted on the frame of the compression chamber, which are adapted to be connected with the plunger and to move therewith during the final compression stroke; wire feeding apparatus mounted 80 on the forward carriage, and wire tying apparatus mounted on the rear carriage; a shaft slidably mounted longitudinally on said carriages and on the forward end of the frame of the machine, and connected by 85 gears to the driving mechanism which operates the compression plunger, so that during the final compression stroke of the plunger the wire feeding needles are brought forward through recesses in the face of the 90 plunger, and the wire into engagement with the looping, twisting and cutting devices, which complete the tie and sever the wire, the final retraction of the plunger serving to return the carriages to their initial position where they are disconnected from the 95 plunger and the apparatus is restored to a position to receive material for the succeeding bale.

The baler chamber which is illustrated in 105 the drawings is of the continuous type, and is formed as a rectangular box-like structure having longitudinal angle iron corner pieces, 2 along the lower edge which form the foundation for the chamber, top longitudinal 110 angle irons, 1, which are connected to the lower angle irons 2 by uprights 1', 2' and

3', and inclosing top and bottom plates. The side plates completing the baling chamber have longitudinal slots 92 and 92'. There is a hopper and opening in the top at C, for feeding. The plunger by means of which the compression of the material is effected, comprises a rectangular box-like frame of which 45 is the face, made to fit within the compression chamber, and slide along the bottom thereof having longitudinal transverse slots therein 50 and 50'.

The mechanism for reciprocating the compression plunger consists of the crank 9 which is rigidly attached to the shaft 8, to which is attached the gear 3, said shaft being rotatably mounted on the frame of the machine. Crank 9 is connected to the bell-crank 11, 12, 13 by the connecting rod 10 at 11'. The bell-crank 11, 12, 13 is pivotally mounted on the frame of the machine at 15' and is connected to the compression plunger by the connecting rod 53 at 52. The operation of this mechanism is as follows: When the gears 3', 5 and 3, Fig. 18, are operated the crank 9 is turned toward the left; this rocks the bell-crank 11, 12, 13 toward the rear of the machine and through the connecting rod forces the plunger rearward; when the crank 9 has reached a position so that the points 9'', 8 and 11'' are in a straight line, the plunger has reached its extreme rearward travel. As the crank then travels toward the front end of the machine, the plunger is withdrawn until the points 9'', 8 and 11'' are again in a straight line, at which point the plunger has reached its extreme forward end of travel. It will be noted that the straight line in which 9'', 8 and 11'' are located, when the plunger is at the extreme inward end of its travel, would be the line indicated by the dotted line X, X', and that the straight line in which 9'', 8 and 11'' are located, when the plunger is at its extreme outward end of travel, would be the line indicated by Y, Y'.

It will be observed that the arc described by the point 9'' on the outward stroke of the plunger is very much less than the arc described by 9'' on the inward stroke of the plunger; this is caused by the relative lengths of the arms in proportion to the distance between the shafts 8 and 15. By this mechanism it requires about one third of the revolution of the gear 3 to make the outward stroke of the plunger, and two thirds of the revolution of said gear to make the inward stroke of the plunger. This is desirable because, on the inward stroke much more power is needed to compress the hay, than on the outward stroke when the plunger is running idle.

The mechanism for reciprocating the carriages is as follows: The guide 56 is rigidly attached to the forward end of the press 1', and to the cross frame 2'. Upon this guide

is slidably mounted the rectangular sleeve 58, upon the inside of this is pivotally attached the connecting rod 58', which is connected to the plunger head at 52. On the outside of the sleeve 58 is the lug 59, which is adapted to engage in the notch 60 in the connecting rod 55, which is pivotally attached to the carriage 30 at 54. The disk 57 is slidably mounted on the bolt 57', Fig. 19, which is rigidly attached to the guide 56, and so adapted that it may be moved outward from the guide 56. The hook 131 is pivotally attached to the carriage 61 at 130, and has a projecting inward lug that slides in the grooved guide 132, which is rigidly attached to the frame of the machine. The hook 135 is pivotally attached to the grooved guide 132 at 133, and is adapted to engage the hook 131. The lug 134, as indicated by the dotted lines, is rigidly attached to the carriage 30 on the inside, and is adapted to disengage the hook 135 from the hook 131, and itself engage the hook 131 as the carriage moves rearward. As the carriages move, the lug 131', on the back of the hook 131, reaches the inclined portion of the groove 132 and raises the hook 131 behind the lug 131''. When the carriage has reached its rearward point of travel and starts on the forward movement, the hook 131 behind the lug 131'' draws the carriage 61 until the lug 131' has reached the inclined portion of the groove 132, at which point the hook 131 drops from behind the lug 131'' and releases the carriage 61. At this point, the hook 135 engages the hook 131 and holds the carriage 61 at rest until the carriage 30 again returns. The member 101 is slidably mounted on the guide 91 in the groove 105. The guide 91 is rigidly attached to the frame of the machine at 93; the hooks 102 and 102' are pivotally attached to the member 101 at 103 and 103', and so adapted that when the rear end of the hooks are closed together they do not cross the grooves in the side of the chambers 92 and 92'. The springs 104 and 104' return them to their original positions. The lever 96 is pivotally attached to the frame of the machine at 97, and the connecting rod 94 is pivotally attached to the lever 96 at 95, and to the member 101 at 95'. The connecting rod 44 is pivotally attached to the carriage 30 at 100, and slidably attached through the slot 99 to the lever 96 at 98. The letter C indicates the hopper above the opening of the baling chamber for feeding the hay.

The mechanism for operating the wire tying and wire feeding mechanisms is as follows. The carriages 30 and 61 are slidably mounted on tracks 31 and 31'; the shaft 16 is rotatably mounted on the frame 2, and upon the opposite end of that shown in Fig. 1 is a spur gear, as shown in Fig. 18, which

is rigidly mounted on same and adapted to mesh in the gear 3 which drives the shaft 16. The grooved sleeve 21 is slidably mounted on shaft 16, and has lugs 25 and 25' on 5 the inward face which are adapted to engage recesses in the spiral gear 24, (Fig. 2,) which is rotatably mounted on shaft 16 and engages the spiral gear 22 which is slidably mounted on shaft 23, and rotatably mounted 10 on the frame 213; the Y shaped lever 17 is pivotally mounted on the frame 213 at 18, and the Y portion is adapted to operate in the groove 26 at 18'; the free end of 17 is diagonal and is adapted to engage the 15 shaft 33 as the carriage 30 moves toward said lever 17 and swings the free end toward the baling press, and thereby slides the sleeve 21 out of mesh with the spiral gear 24; when the carriage 30 moves in the opposite 20 direction the lever 17 is drawn into the position shown by the dotted lines in Fig. 2, by the spring 24'. This engages the sleeve 21 with the spiral 24 and through the spiral 22 the shaft 23 is revolved. The longitudinal 25 shaft 23 is rotatably and slidably mounted on the carriage 30 at 30' and rotatably mounted on the carriage 61, this permits the movement of carriages 61 and 30 parallel with the frame of the machine, and 30 at the same time operates the wire tying and feeding mechanism.

The mechanism for feeding the wire through the baling chamber consists of two angle shaped needles 34 as shown in Figs. 35 10 and 16, rigidly mounted on the shaft 33 which is rotatably mounted on the carriage 30, which is mounted on the same side of the machine as the wire tying mechanism, and is adapted to pass through the baling 40 chamber to the other side of the machine, and when swung forward on the shaft 33, the curved portion of the needle is adapted to swing back through the baling chamber through the grooves 50 and 50' in the compression 45 plunger, and slots 92 and 92' in the side of the baler, and corresponding slots on the opposite side. The forward end of each needle is provided with two rollers, 160 and 161, which act as pulleys around 50 which the wire moves.

The mechanism for reciprocating the needle consists of the crank 32 rigidly attached to the shaft 33, the crank 154 which is rigidly attached to the shaft 41, the connecting 55 rod 156 pivotally connecting these cranks, the bevel gear 39 rigidly attached to the shaft 40, and the segmental bevel gear 38 slidably mounted on the shaft 23. When the needles are at rest outside the baling 60 chamber, the gear 39 is in engagement midway of the segment of the gear 38; the gear 38 revolves until the gear 39 has passed off of the segment at which time the points 155, 41 and 43 are in a straight line, and the 65 needles are brought to rest until, the wire

tying process has been completed, at which point the segment at the gear 38 again engages the gear 39, and the crank 154 revolves until the points 41, 155 and 43 are again in a straight line, at which point the 70 mechanism is disconnected, as has been heretofore explained, from the mechanism driving the compression plunger, and at which point the gear 39 has passed through one half of the segment of the gear 38; the wire 75 tying and feeding mechanism is then at rest until it is desired to tie another bale.

The mechanism for tying the wires is as follows: On the rear end of the shaft 23 is rigidly mounted a duplicate of the gear 38, 80 which cannot be seen in Fig. 1, but which is shown in Fig. 20, and designated by 38'. This gear is rigidly mounted on the shaft 23, which shaft is rotatably mounted in the frame 61, and which gear is adapted to engage a duplicate of the gear 39, which cannot be seen in Fig. 1, but which is shown in Fig. 20, and which is rigidly mounted on the shaft 68, to which is rigidly attached the gear wheel 64, which has on its periphery two segmental bevel gears 69 and 144, (Fig. 7) which are adapted to engage in the bevel gear 78. 69 engages 78 on the inward side, revolving same in one direction, and 144, which is indicated by the 90 dotted lines, the teeth of which project inwardly, engages it on the outward side and revolves it in the other direction. Gear 64 also has on its periphery, the spur segment 143 which is adapted to engage the gear 77, 100 which operating through the shaft 141 and the gear 70, revolves the twisting head 114; the gear 64 also has on its periphery three segmental guides, 149, 145 and 150; 149 is adapted to engage the groove 48 on the gear 105 78, and hold same at rest during the operation of the gear 77; the guide 150 is adapted to engage the guide 150' on the gear 77, 110 which holds same at rest during the remainder of the revolution of 64; the guide 145 is 115 adapted to engage the groove 147' in the member 147, which is rigidly attached to the gear 78; the gear 77 is rigidly mounted on the shaft 141 upon which is mounted the gear 70 which engages a duplicate gear 70', 120 which is rotatably mounted on the shaft 142; the gear 70 also engages the segmental twisting head with teeth in its periphery 114 which is rotatably mounted on the frame 61 in the hollow trunnion 110, Fig. 3; the gear 70' also engages the segmental twisting head with gear teeth in its periphery 114, which is rotatably mounted on the frame 61 in the hollow trunnion 110'.

It will be understood, that it is necessary 125 that the wire feeding and the wire tying mechanism move forward simultaneously with the compression plunger, for the reason that with the continuous operation of the mechanism driving the plunger, the 130

plunger stands at its inward end of travel only momentarily, and does not give sufficient time at the point at which it is stationary to feed the wire through the baling chamber, tie the ends and sever same, and return the needle to the original position. If this were done, it would require such high speed that it would make the machine impractical; for this reason it is necessary to move the wire feeding mechanism and the wire tying mechanism forward with the plunger during the operation of the tying and feeding machinery; for this reason, two sliding carriages are mounted on the frame 5 of the machine, which are connected by a grooved shaft 23, on which are slidably mounted gear 38 for operating the feeding mechanism, and a duplicate of the gear 38. The wire tying mechanism consists of two 10 rotary looping members mounted on the frame 61 and 63; the wire tying mechanism comprises a rotary looping head which is adapted to loop the ends of the wire to be secured together about a central pin, and the rotary twisting head which includes said pin, together with appropriate clamping devices for holding the looped wire on opposite sides of said pin; each of said wire 15 looping members consists of an annular plate 20 provided with gear teeth on its periphery, rotatably mounted upon a central hollow journal or sleeve, in which is rotatably mounted the wire twisting pin; the looping members 74 and 74' contain two wire clamping 25 hooks 73 and 73', located diametrically opposite, said hooks having upon one edge a clamping face, and on the other edge a shear, also two shearing members 72 and 72', which are located diametrically opposite 30 and pivoted on the same axis, and attached so that the shearing edge of the shearing member, and the shearing edge of the clamping member are brought in contact, as shown in Figs. 11 and 3; the looping member 35 also has two wire guides 82 and 82', which are pivotally mounted so that when they are not needed they drop down below the surface, and when they are needed to hold the wire in position, a hook is brought 40 up above the surface. The mechanism for operating these wire clamping, shearing and guiding members consists of spring dogs 45 164, 165 and 166, Figs. 11, 12 and 13, which engage teeth on the rearward side of the clamping, shearing and guiding members; 50 said dogs are attached to the annular plate 163, which is located about one inch from the rearward side of the looping member, and the face of which acts as a guide for 55 the wire clamping, shearing and guiding members, and holds same locked, either open or closed, as is required; when the looping member is revolved these spring dogs engage the teeth and open and close them, as 60 65 required.

The mechanism for operating the looping members consists of the gear 75 which is rigidly mounted on shaft 80 in the frame 63, and is adapted to engage the teeth of the looping members 74 and 74'. On the opposite end of said shaft is gear 78 which is adapted to engage the segmental gear 69 on the inward side of said gear 78, which revolves the looping members clock-wise, two thirds of a revolution, which closes one 75 wire clamping member over the wire, and opens the opposite wire shearing member and loops the wire around the rotary pin; gear 78 is also adapted to engage the segmental gear 144 on the opposite side from 80 the segment 69, which reverses the motion of the looping members and returns them to their original position one half revolution ahead, and opens one wire clamping member and releases the twisted wires and 85 closes the opposite wire shearing member, which severs the wire between the twisted portion and the wire extending to the needle. The wire twisting mechanism consists of a segmental spur gear with two teeth cut 90 away, one on each side of a single tooth, said cut away portions extending past the center of the gear as indicated by 114' in Fig. 8; said gear is mounted in a hollow trunnion, the tooth 71 extending out past 95 the face of the looping member, as indicated in the dotted line in Fig. 8; the bearings for this gear consist of two grooves and two extensions, one each on each face of said gear; said grooves and extensions being indicated by 152 and 152'; these grooves and extensions are adapted to mesh in two segmental grooves and extensions on the frame 100 61 extending into the hollow trunnion; these grooved bearings are necessary in order that 105 when the gear 114 is revolved, it will turn past the cut away portion in both the gear and the bearing without a jar, or without slipping cogs; the gear 70 is adapted to engage the segmental gear 114, and the teeth 110 on both gears are exceptionally long so that the teeth on gear 70 mesh in close to the center of the gear 114, and in this way, when the segmental portion of the gear 114 is about to pass into the gear 70, it is turned 115 past the cut away portion without a jar; the gear 70 is rigidly attached to the shaft 141, upon which is rigidly mounted the gear 77, Fig. 7, and which is adapted to engage the segmental gear 143 of the gear 64; this 120 segment turns the gear 77 one complete revolution, which operating through the gear 70 turns the gear 114, three complete revolutions and leaves it at rest in the same position from which it started. 125

The wire hooks or guides 89 and 89', Figs. 1 and 3, are adapted to hold the wire across the face of the machine as shown in Fig. 3, and consist of a rotary member with two hooks *a* and *b* diametrically opposite equal 130

distance from the center; this member is rigidly attached to the shaft 84, to which is attached the spiral 85, which engages the spiral 86 which is rigidly attached to the shaft 67, to which is attached the bevel gear 66, which meshes in the bevel gear 65 which is rigidly attached to the shaft 68; when the looping member 74 starts to revolve clock-wise, Fig. 3, it requires about two inches of slack in the wire 121 to permit the wire to be brought directly across the center of the member; to provide for this slack, the worm 86 on the face of the segmental spiral 83 turns the spiral 85 sufficiently to give out this two inches of slack. During the twisting operation no slack is required, and the worm 85 slides on the straight portion of 83 until the looping member 74 starts in a reverse motion to sever the wire and release same, at which point the spiral 87 engages the spiral worm 85 and turns the wire holding member 89 the remainder of one half revolution, which releases the wire from the hook and places the opposite hook in the position of the previous hook, so that when the needle is returned back through the baling chamber, this hook catches the wire and holds it, as is indicated in Figs. 3 and 6; that is the hook *b* is in the same position that hook *a* was when the operation commenced.

When the needle returns to rest preparatory to receiving further charges of hay, the wires are drawn diagonally across the baling chamber directly beneath the opening for receiving the hay; this would interfere with feeding the hay into the chamber, and in order to overcome this it is necessary to provide means for forcing the wire rearward against the bale and from beneath the opening; this is done by sliding carriages mounted on the side of the baling chamber, one of which is shown in Fig. 1, and indicated by 101, the other of which is a duplicate of 101, 45 is mounted on the reverse side of the machine; 101 is slidably mounted on the track 91 and guide 105. Pivotal mounted on the top and bottom of the carriage, are two dogs 102 and 102', which are adapted to oscillate across the slots 92 and 92' in the side of the chamber through which the wire passes; these dogs are held across said slots by springs 104 and 104', and are so adapted that as the carriage moves past the wire toward 55 the front of the machine, dogs will spring down and let the wire pass, and when the carriage moves toward the rear, dogs spring across the slots and take the wire with them. The carriage 101 is slidably operated by the 60 connecting rod 94, which is connected to the lever 96 at 95, which is pivotally attached to the frame of the machine at 97 on the lower end of which is slidably mounted the lever 44 at 98; when the carriage 30 moves rearward 65 the carriage 101 is moved forward and when

the carriage 30 is moved forward the carriage 101 is moved rearward; in this way the dogs are moved apart behind the wire when the tying mechanism is at its extreme rearward stroke, and as the carriage returns the 70 wire is forced rearward.

The process of clamping, looping, twisting and shearing the wires is as follows: The wire clamp 73 and 73' and the shear 72 and 72', Fig. 11, are pivotally mounted in the 75 wire looping members 74 and 74', Fig. 3, near the periphery of said members diametrically opposite each other, and operated by the spring dogs 164 and 165.

When the needle is at rest after having 80 brought the wires across the face of the looping member 74 so that the wire which passes to the bale from the needle head, is drawn close to the looper and above the twisting pin, Figs. 3 and 16, the looper head is started to revolve clock-wise by the mechanism before described; this brings the teeth on the rear of the wire clamp 73 in contact with the spring dog 164, which closes the hook of the wire clamp 73 over the wire, and 85 brings it from the dotted line position to the full line position as indicated in Fig. 12; at the same time, the shear 72 comes in contact with the dog 165, which closes same and 90 brings it from the full line position to the dotted line position in Fig. 13. The continued revolution of the looper head brings it to the position indicated in Fig. 4, with the wires looped together around the pin, and the free end of the wire passing back to the 100 needle passes around the hook 82' which was brought into engagement with the wire as said hook passed over the spring dog 166; the wire twisting mechanism is then brought into engagement, which twists the wires by 105 the mechanism previously described; the motion of the looper head is then reversed and the clamp 73' comes in contact with the spring dog 164, which opens same and releases the wire, and the shear 72 comes in 110 contact with the spring dog 165, which causes the shearing face of 72 to cross the shearing face of the wire hook 73, and severs the twisted wire from the wire passing to the needle. Upon the reverse motion of the 115 looper, wire guide 82' comes into engagement with the spring dog 166, which causes it to drop down below the face of the looper head; at this point when the looper head is at rest it is just one half revolution advanced clock-wise from what it was when the operation was commenced; that is 72 and 73 are in the same position that 72' and 73' were and 82 is in the same position that 82' was when operation commenced.

The operation of the apparatus as hereinbefore described, is substantially as follows: Preparatory to receiving the first charge of hay or the like, the compression plunger is at the forward end of the stroke, and the 130

curved end of the wire feeding needles is outside the baling chamber opposite from the pivoted end; the needles are so hung that the straight portion of the needles passes 5 through the baling chamber, and when the needle is at rest and out of operation, the curved portion is entirely outside of the baling chamber on the opposite side, the straight portion passes through the baling 10 chamber back of the compression plunger 45; the connecting rod which operates the plunger swings between the two needles as shown in Fig. 1.

The wire is attached under the clamping 15 hook 73', Fig. 3, passes around the hook α of the members 89 and 89', thence across the face of the looping members 74 and 74', and behind the dog 102', thence across the baling chamber through the grooves 92 and 20 92', thence around the rollers 161 and 160, as shown in the full lines, Fig. 10, thence to the spools at the forward end of the machine, Fig. 16. Successive charges of hay are fed into the baling chamber through the 25 hopper C, and compressed in the compression chamber; as the hay is fed in, the rear end of the bale pushes the wire rearward and when the bale has become of sufficient length, the disk 57 is moved sidewise from 30 beneath the guide 56 on the bolt 57', by hand or otherwise; this permits the connecting rod 55 to drop down on the lug 59, and as the guide 58, which is connected to the compression plunger 45 by the connecting rod 35 58', moves rearward, the notch 60 drops over the lug 59 and operating through the lever 55 moves the carriage 30 rearward. As soon as the carriage starts, the shaft 33 passes from behind the lever 17 and the spring 24 40 brings the lever 17 to the position indicated in the dotted lines, Fig. 2; this slides the grooved sleeve 21 on the shaft 16 toward the baling chamber, and the lugs 25 enter the recesses in the face of the spiral gear 24; 45 this brings the gear 24 into operation which through the spiral gear 22, starts the shaft 23 revolving clock-wise; the segmental bevel gear 38 being slidably mounted on the shaft 23, starts the bevel gear 39 and through the 50 shaft 40, revolves the crank 154, and through the connecting rod 156 and the crank, 32, revolves the farther end of the needle forward. When the carriage has reached the 55 position so that the points of the needles are opposite the grooved guides 50 and 50' in the plunger face, the needle passes through them, and the lug 134 disengages the hook 135 from the hook 131, and the carriage 30 comes in contact with the carriage 61, moving 60 it rearward, and the grooved guide 132 raises the hook 131 behind the lug 134'. At this point the plunger face is opposite the face of the rotary looping members 74 and 74', and the needle passes in front of this 65 face above the wire twister 71, as shown in

Fig. 4, and below the hook 73, as shown in Fig. 16. When the needle has reached the extreme end of the stroke as indicated in Fig. 4, the bevel gear 39 passes off the segmental gear 38, and the guide 159 on the gear 39 passes onto the guide 158, on the gear 38, as indicated in Fig. 9, and locks the gear 39 at rest. At this point the segmental gear 38 on the end of the shaft 23, as shown in Fig. 9, passes off of the guide 158, and the teeth of the gears 38 and 39 in contact; this revolves the shaft 68, Fig. 1, which revolves the gear wheels 64. The segmental bevel gear 69 in Fig. 7 comes in contact with the bevel gear 78, this revolves the shaft 80, the gear 75, and the segmental looping gear members 74 and 74' clock-wise; this brings the wire clamping member 73, Figs. 1 and 3, over the wire 120, Fig. 3, and as the teeth on the wire clamp come in contact with the spring dog 164, as shown in Fig. 12, the wire clamp is brought into the position indicated in the full lines, which clamps the wire against the side of the member in which the clamp rotates; as 90 the looper starts to revolve, the segmental worm 86 turns the spiral 85 sufficiently to give out what slack is needed for looping and twisting the wire; when the segment 69 has passed off of the element 164, the rotary 95 looping member 74 has turned a little more than one half revolution, and the wires are brought into the position indicated in Fig. 4; at this point the guide 48 on the gear 78 comes in contact with the guide 149 on 100 the gear 64, and holds the gear 78 at rest; at the same point, the segmental spur gear 143 on the gear 64 comes in contact with the teeth on the gear 77; this revolves the shaft 141, and through that the gear 70, and 105 as shown in Fig. 8, the segmental twister gear 114; when the gear 70 has turned one complete revolution, the gear 114 has turned three revolutions, and is brought to the original position from which it started and 110 has twisted the wire as shown in Fig. 5; at this point the segmental gear 143 has passed off of the gear 77, and the guide 150' has come in contact with the guide 150, which holds the twisting mechanism at rest; 115 at the same point the segmental teeth 144, Fig. 7, come in contact with the opposite side of the gear 78 from the segment 69, which revolves gear 78 in the opposite direction, and operating through the shaft 80 and the gear 75, revolves the looping members 74 and 74' in the opposite direction; this brings 120 the wire cutting member 72 as shown in Figs. 6 and 12, in contact with the spring dog 165, and moves the cutting member 125 from the dotted line to the full line position as indicated in Fig. 13; this brings the shearing edge of the member 72 across the shearing edge of the member 73, and severs the twisted wire, and at the same time the 130

wire clamp 73" comes in contact with the spring dog 164, which opens it from the full line position to the dotted line position, as shown in Fig. 12; this releases the other end 5 of the wire as shown in Fig. 6, and the wire guide 82 engages dog 166, which releases that wire. During the reverse motion of the looper the spiral 87 engages the spiral 85 and revolves the wire holding member the 10 remainder of one half revolution, which releases the wire and places the opposite hook in position to receive the wire before the return of the needle. After the segmental gear 144 has passed off of the gear 78 the 15 guide 145 passes into the groove 147' on the guide 147; this holds the wire looping members 74 and 74' at rest; at this point the segment 157 of the gear 38' has passed off of the gear 39', and the guide 158 on the 20 gear 38 comes in contact with the guide 159 on the gear 39 and holds the shaft 68 at rest; at this point the segment of the gear 38 comes in contact with the bevel gear 39, which revolves the shaft 41, and through the 25 connecting rod 156 and shaft 33, returns the needles to their original position, leaving the wire attached to hook b; at the same time the compression plunger crank will have passed center, and the plunger will be 30 returning toward its original position; this will bring the lug on the hook 131 in the groove 132, to the slanted portion, which will drop the hook 131 below the lug 134, and release the carriage 61; the hook 135 35 will engage the hook 131, and hold the carriage 30 at rest; the carriage 30 will move on to its original position, when the slanted end of the connecting rod 55 will come in contact with the disk 57, which will raise 40 the connecting rod and free the lug 59 from the notch 60; at the same time the shaft 33 comes in contact with the slanted end of the lever 17 which moves that from the dotted line to the full line position as shown in 45 Fig. 2; this slides the grooved sleeve 21 on the shaft 16, to the full line position, and disengages the lug 25 from the spiral gear 24, and at the same time the finger 26 sliding through the guide 27, enters a recess in 50 the face of the spiral gear 22, which locks that at rest; this has disengaged all the wire feeding and wire tying mechanism from the baling mechanism, and permits the baling machine to continue operating the 55 same as though there were no wire tying and wire feeding machinery attached. As the carriage 30 advances rearward, the end of the slot 99 in the connecting rod 44, comes in contact with the bolt 98 in the lever 96; 60 this forces the sliding member 101 forward sufficiently far to come in front of the wire, and as the carriage 30 returns to its original position, the other end of the slot 99 comes in contact with the bolt 98, which slides the 65 member 101 rearward and brings the wire

which is drawn across the baling chamber, underneath the opening in the top by the needles as they pass outward, rearward against the end of the bale. It is contemplated that a duplicate of this sliding mechanism for forcing the wires rearward, may be also placed on the opposite side of the machine, and operated by extending the shaft 97 underneath the baler, and projecting an arm upward, the same as indicated, 70 both sliding members being driven by the same mechanism.

After the bale has reached a sufficient length, either by hand or by machinery, the disk 57 is moved out from underneath the 75 end of the connecting rod 55, which lets that drop down on to the lug 59, and sets the entire wire feeding and wire tying mechanism in operation.

What I claim is:

1. A baling press, comprising a compression chamber, a plunger operable therein, two reciprocatory carriages mounted on the frame of the compression chamber and adapted to stand at rest during the reciprocation of the plunger except during the final compression stroke of the same, wire feeding mechanism mounted on one carriage, wire tying mechanism mounted on the other carriage, means to reciprocate said carriages 85 with the plunger, and means to actuate the feeding and tying mechanism.

2. A baling press, comprising a compression chamber, a compression plunger operable therein, two reciprocatory carriages 90 mounted on the frame of the compression chamber and adapted to stand at rest during the reciprocation of the plunger except during the final compression stroke of the same, wire feeding mechanism mounted on one carriage, wire tying mechanism mounted on the other carriage, means rendered operative by the motion of the compression plunger to reciprocate the carriages, means to actuate the wire tying and wire feeding mechanism 95 simultaneously with the reciprocation of the carriages.

3. A baling press, comprising a compression chamber, a reciprocatory carriage mounted thereon, wire feeding needles pivotally mounted on said carriage, a compression plunger having transverse slots in its face and operable in the compression chamber, means to intermittently connect the carriage with the plunger, and means operative 115 to oscillate the needles through the slots in the plunger simultaneously with the reciprocation of the carriage and the plunger.

4. A baling press, comprising a compression chamber, a compression plunger operable therein, a reciprocatory carriage mounted on the chamber, wire tying mechanism mounted thereon, a second reciprocatory carriage, wire feeding mechanism mounted thereon, a slidably mounted longitudinal 120

shaft to actuate the wire feeding and tying mechanisms, and means for sliding the shaft.

5. A baling press, comprising a compression chamber, a reciprocatory plunger operable therein, two carriages mounted on said chamber, wire feeding mechanism mounted on one carriage, and wire tying mechanism mounted on the other, means for connecting the carriages with the plunger to cause them 10 to reciprocate during the final compression stroke of the plunger, a gear segment and pinion mounted on the wire feeding carriage to reciprocate the wire feeding needles.

6. A baling press, comprising a compression chamber, a plunger arranged therein, two carriages mounted on said chamber, means for connecting the carriages with the plunger to cause same to reciprocate during the final compression stroke of the plunger, 15 a segment and pinion mounted on the wire feeding carriage to operate the needles, means for actuating said segment during the forward motion of the carriages, and means for rendering the actuating means inoperative during the return movement.

7. A baling press comprising a compression chamber, a compression plunger operable therein and having a solid portion and transverse grooves in its face, means for operating the plunger, a carriage mounted on one side of the chamber, wire feeding needles mounted on the side of the carriage which, when inoperative, extend through the baling chamber between the solid portion of the 30 same and the aforementioned operating means, means for oscillating the fingers so that their forward ends pass around the solid portion of the plunger and through the grooves in the face of the same between the solid portion and the compressed material.

8. A baling press, comprising a compression chamber, carriages mounted thereon, wire tying mechanism mounted on one carriage, wire feeding needles mounted on the other carriage, means to throw into operation the wire tying mechanism, and the wire feeding needles during the forward stroke of the plunger, and means to disengage same 50 during the return stroke.

9. A baling press, comprising baling mechanism, wire tying and feeding mechanism mounted on sliding carriages, a sliding clutch co-operating with the baling mechanism, the tying mechanism and the feeding mechanism, means to throw the clutch into engagement during the forward movement of the carriage, and means to disengage said clutch during the return movement of said 60 carriage.

10. A baling press, comprising a compression chamber, two reciprocatory carriages, wire feeding mechanism mounted on one carriage, wire tying mechanism mounted on the other carriage, means for engaging the same

together, means to lock said wire tying and wire feeding mechanisms at rest when disengaged.

11. A baling press comprising a compression chamber, a compression plunger operable therein, a reciprocatory carriage mounted on said chamber, wire tying mechanism mounted on said carriage, a second carriage mounted on the chamber independent of the compression plunger, which carriage stands 75 at rest during the reciprocation of the plunger except during the final compression stroke, wire feeding mechanism mounted on said second carriage and spiral gears mounted on the compression chamber to render the 80 tying mechanism and feeding mechanism operative during the reciprocation of the plunger.

12. A baling press, comprising a compression chamber, a compression plunger operable therein, two reciprocatory carriages, wire tying mechanism mounted on one carriage, wire feeding mechanism mounted on the other carriage, a shaft slidably associated with said carriages and on the frame of the 85 machine, means to rotate the shaft to operate the wire tying and wire feeding mechanisms simultaneously with the reciprocation 90 of the plunger.

13. A baling press, comprising a compression chamber, compression plunger operable therein, two reciprocatory carriages mounted on said chamber, means for reciprocating said carriages with the plunger, means for engaging the rear carriage with the forward carriage during the latter end of the rearward and first end of the forward stroke, means for disengaging said carriage during the rearward stroke.

14. A baling press, comprising a compression chamber, two carriages slidably mounted thereon, wire feeding mechanism carried by one carriage, wire tying mechanism carried by the other carriage, means for reciprocating the carriages, and means for locking said carriage at rest when not in operation.

15. A baling press, comprising a compression chamber, a plunger operable therein, two reciprocatory carriages mounted on said chamber, a hook loosely mounted on rear carriage extending forward, an offset grooved guide mounted on the compression chamber in which a projection on said hook operates to raise and lower the free end of 115 said hook as the carriage moves, and a hook on the forward carriage extending rearward, and adapted to engage the hook on the rear carriage, means for reciprocating said carriages with the plunger, substantially, as 120 shown and described.

16. A baling press comprising a compression chamber, a compression plunger operable therein, a rotatably mounted crank, a V-shaped bell crank pivotally mounted on 130

- the lower compression chamber at its point, the two arms of the bell crank extending upwardly, a connecting rod between one of said arms and the rotatably mounted crank, 5 a connecting rod between the other arm of the bell crank and the compression plunger, and means for rotating said first mentioned crank.
17. A baling press, comprising a compression chamber, a compression plunger, a reciprocatory carriage mounted thereon, wire feeding needles mounted on said carriage, wire holding fingers, a second reciprocatory carriage, wire guiding fingers mounted on 10 the last-mentioned carriage, means rendered operative to cause the wire holding fingers to take the wire from the wire feeding needles and force it rearward.
18. A baling press comprising a compression chamber, wire feeding mechanism, a rotary wire looping member, and wire clamping and cutting members pivotally mounted on the looping member near its periphery so that they rotate with the same 15 on axes approximately at right angles to the axis of the looping member.
19. A baling press comprising a compression chamber, wire feeding mechanism associated therewith, a rotary wire looping member, wire clamping and cutting members mounted on axes approximately at right angles to the axis of the looping member, and a guide plate located adjacent to the looping member and adapted to lock 20 the clamping and cutting members in operative or inoperative positions.
20. A baling press comprising a compression chamber, a rotary looping member, wire clamping and cutting members mounted on the looping member so that they rotate with the same on axes approximately at right angles to the axis of the looping member, means to actuate the looping member, and means for locking the same at rest 25 when it is not in operation.
21. A baling press including a compression chamber, a movable carriage, a rotary looping member and wire clamping and cutting members mounted on said member and located at various distances from said chamber, the clamping member farthest from the compression chamber being adapted to receive the wire.
22. A baling press including a compression chamber in which a plunger is operable, a rotary looping element, a clamping member mounted on the looping member to one side of the center, and wire feeding needles adapted to pass across the face of the 30 looping element at right angles to the axis of said element and deliver the wire to the clamping member.
23. A baling press including a compression chamber, a plunger operable therein, 35 means for feeding wire around the bale, a rotary looping element, a wire guiding member mounted therein, and means for twisting the wire, the guiding member being arranged to hold the free end of the wire out of operation during the looping and twisting operation.
24. A baling press including a compression chamber, means for feeding wire around the bale, a wire tying member comprising a looping member adapted to rotate in both directions, and wire guiding members, each of which is adapted to alternately open on the movement of the looping member in one direction and to close upon its movement in the opposite direction.
25. A baling press including a compression chamber and wire tying mechanism comprising a rotary looping member, wire clamping and cutting members mounted on the looping member so that they rotate with the same on axes approximately at right angles to the axis of the looping member, means to actuate the looping member, and means for locking the same at rest when not in operation.
26. A baling press including a compression chamber, wire feeding mechanism and wire tying mechanism comprising a segmentally recessed twisting head, gear teeth deeply recessed in the periphery thereof, a gear wheel, the teeth of which are adapted to deeply mesh with the teeth of the twisting head so that the ends of the teeth pass close to the center of the twisting head, and a tooth in said recess.
27. A baling press including a compression chamber, wire feeding mechanism and wire tying mechanism comprising a segmentally recessed twisting head, gear teeth deeply recessed in the periphery thereof, a gear wheel, the teeth of which are adapted to deeply mesh with the teeth of the twisting head so that the ends of the teeth pass close to the center of the twisting head, a tooth in said recess, means to actuate the twister head, 100 and means to hold the twister head at rest when not in operation.
28. A baling press including a compression chamber, wire feeding mechanism and wire tying mechanism comprising a wire looping head, a wire tying head, a rotatably mounted wire holding finger, and means rendered operative by the rotation of the finger to allow the necessary slack in the wire during the looping and twisting of the same.
29. A baling press including a compression chamber, a rotary looping head, a wire twisting member, wire feeding needles adapted to pass through the chamber and across the face of the looping member, a wire holding finger rotatably mounted and having two hooks equidistant from the center and diametrically opposite each other, and means to actuate the finger to release the twisted wire and engage the next wire.

as the needles pass back across the face of the looping member.

30. A baling press comprising a compression chamber, a compression plunger, a looping member, a twisting head, means to revolve said looping member in one direction, means to hold the same at rest during the twisting operation, means to revolve the looping member in the opposite direction 10 and means to hold the same at rest.

31. A baling press including a compression chamber, a compression plunger, wire looping member, means to rotate the looping member more than one half revolution to 15 loop the wires, means to rotate the looping member less than one half revolution in the opposite direction to sever and release the wires.

32. A baling press comprising a compression chamber, compression plunger, a rotary looping member, two wire clamping members located in the looping member near the periphery of the same on axes approximately perpendicular to the axis of the looping 25 member.

33. A baling press comprising a compression chamber, compression plunger, a rotary looping member, two wire clamping members located in the looping member near the 30 periphery of same on axes approximately perpendicular to the axis of the looping member, two wire cutting members mounted adjacent to and on axes concentric with said wire clamping members.

34. A baling press comprising a compression chamber, a compression plunger, a rotary looping member, wire clamping and wire shearing members mounted thereon on axes approximately perpendicular to the axis 40 of the looping member, means to actuate the wire clamping and wire shearing members upon the revolution of the looping member.

35. A baling press comprising a compression chamber and a compression plunger, a 45 rotary looping member, wire clamping and wire shearing members mounted thereon on axes approximately perpendicular to the axis of the looping member, means to actuate the shearing and clamping members so that 50 when the looping member is rotated in one direction one wire clamping member closes and the opposite wire shearing member opens and means to actuate the wire clamping and wire shearing members so that when the 55 looping member is rotated in the opposite direction the other wire clamping member opens and its opposite wire shearing member closes.

36. A baling press comprising a compression chamber, a compression plunger, a rotary looping member, a wire clamping member having on one face a clamping edge and on its opposite face a shearing edge, mounted on an axis approximately at right angles to 65 the axis of the looping member.

37. A baling press comprising a compression chamber, a compression plunger, a wire clamping member having on one face a clamping surface and on the other face a shearing edge, a wire shearing member having on one face a shearing edge mounted adjacent to and concentric with the wire clamping member. 70

38. A baling press comprising a compression chamber, wire feeding and wire tying 75 mechanism mounted theron, a wire twisting head having segmental projections on both sides of the same, and segmental grooves adapted as bearings to said projections so that said twisting head may be revolved, 80

39. A baling press comprising a compression chamber, a compression plunger, wire feeding mechanism, wire tying mechanism comprising a wire looping member, a wire twisting head, a gear wheel, and comprising 85 multiple segmental cog wheels and segmental guides adapted to rotate the looping member in one direction to hold the same at rest, to revolve the twister head and to hold the same at rest and to rotate the looping 90 member in the opposite direction and to hold the same at rest.

40. A baling press comprising a compression chamber, a compression plunger operable therein, a reciprocatory carriage, wire 95 feeding mechanism mounted thereon, another reciprocatory carriage, wire tying mechanism mounted thereon, means to engage the first mentioned carriage with the said plunger and reciprocate simultaneously 100 with the same, means to engage the second mentioned carriage with the first mentioned carriage and reciprocate the same together, means to disengage said carriages, means to disengage the first carriage from said plunger and means to hold said carriages at rest 105 when inoperative.

41. A baling press comprising a compression chamber, wire feeding mechanism, wire tying mechanism, a rotatably mounted 110 segmentally recessed gear wheel with one tooth in said recess adapted as a gear tooth and also as a pin around which the wires are looped, and means to rotate said gear wheel. 115

42. A baling press comprising a compression chamber, wire feeding mechanism, wire tying mechanism, a wire looping member, a wire clamping member pivotally mounted in the same and having teeth 120 adapted to engage a spring tooth mounted on an adjacent guide plate, and means to rotate said looping member to oscillate the clamping member.

43. A baling press comprising a compression chamber, wire feeding mechanism, wire tying mechanism, a wire looping member, a wire shearing member pivotally mounted in the same and having teeth 125 adapted to engage a spring tooth mounted on 130

an adjacent guide plate, and means to rotate said looping member to oscillate the shearing member.

44. A baling press comprising a compression chamber, a compression plunger operable therein, wire tying mechanism including a looping member rotatably mounted, wire feeding mechanism including needles pivotally mounted, the axis of which is a

line that would cross the axis of the looping 10 member if extended.

In testimony whereof I affix my signature, in presence of two witnesses.

WALLACE CASWELL.
